(57) The ornamental design for a side-panel, as shown and described.

DESCRIPTION

FIG. 1 is a perspective view of the side-panel.

FIG. 2 is a front elevation view of the side-panel.

FIG. 3 is a top plan view of the side-panel.

FIG. 4 is a bottom view of the side-panel.

FIG. 5 is a left side view of the side-panel; and,

FIG. 6 is a right side view of the side-panel.

The broken lines of FIGS. 1-6 are included for the purpose of illustrating environmental structure and form no part of the claimed design. The rear-elevational views form no part of the claimed design.

The broken lines immediately adjacent the shaded areas having alternating long and short dashes represent the bounds of the claimed design where all other broken lines are directed to environment and are for illustrative purposes only.
